ATTORNEYS.

UNITED STATES PATENT OFFICE.

GEORGE R. CUDLISS, OF LOS ANGELES, CALIFORNIA.

TALKING-MACHINE TABLE.

1,284,249.

Specification of Letters Patent. Patented Nov. 12, 1918.

Application filed May 15, 1918. Serial No. 234,656.

To all whom it may concern:

Be it known that I, GEORGE R. CUDLISS, a citizen of Great Britain, and resident of Los Angeles, county of Los Angeles, State 5 of California, have invented certain new and useful Improvements in Talking-Machine Tables, of which the following is a specification.

My invention relates to talking machines 10 in which the records used are disk shaped, which disks are mounted horizontally upon a flat rotating table when in use on the machine.

Heretofore in the use of talking machines 15 of the above character it has been found both difficult and awkward in removing the disks from the table after the same have been in use and considerable breakage has resulted.

It is the object of my invention to provide 20 means for easily and quickly removing the disks from the tables of talking machines, which will be cheap, simple and efficient and which will obviate all danger of breakage.

I accomplish the above and other objects 25 as will appear hereinafter by the device described herein and illustrated in the accompanying drawings forming a part hereof in which:

Figure 1 is a top plan of a table equipped 30 with my invention.

Fig. 2 is an edge elevation, partly broken away, of Fig. 1.

Fig. 3 is a view similar to Fig. 2, showing 35 a disk being removed.

Fig. 4 is an edge elevation, partly broken away, of Fig. 1, with a modified form of my invention.

While I have shown and will describe my 40 preferred form of my device it will be understood that I do not limit myself to such preferred form but that various changes and adaptations may be made without departing from the spirit of my invention.

Referring to the drawings, 5 is a talking 45 machine table of the usual construction, in which is provided a radially extending elongated aperture 6, which aperture extends from near the outer edge to near the center. Mounted in aperture 6 is a filler bar 7, which 50 is of a size and shape to snugly fit said aperture but to move freely therethrough. Filler bar 7 is held positioned by means of a flexible spring 8, one end of which is riveted or 55 otherwise secured to the under side of said

bar and its other end is secured in like manner to the underside of table 5, the spring and bar being so adjusted that the upper face of the bar 7 is normally flush with the upper face of table 5. The upper face of 60 table 5 and bar 7 is covered in the usual manner with a fabric covering 9.

In Fig. 4 I have shown the filler bar and spring formed from one continuous piece of flexible spring metal. In this form I make 65 the bar of substantially U-shape, the width of the U being equal to the thickness of the table proper, and one leg being longer than the other for securing to the under side of the table. 70

In the operation of my device the parts will be in the position shown in Figs. 1 and 2, with the disk 10 in position thereon.

When it is desired to remove the disk the operator will place the end of his finger upon 75 the upper face of bar 7 near its outer end and press downwardly which will enable him to insert his finger under the edge of the disk when the same may be easily and quickly removed. 80

Having described my invention what I claim is:

1. In a table for talking machines a radially extending elongated aperture therethrough and a yieldable filler bar for said 85 aperture.

2. A table for talking machines having a radially extending elongated aperture therethrough near its outer edge; and a yieldable filler bar for said aperture. 90

3. A table for talking machines having an opening therethrough near its periphery and a downwardly yieldable filler bar for said aperture.

4. A table for talking machines having an 95 opening therethrough near its outer edge and a filler bar for said opening adapted to be pressed downwardly to permit the insertion of a finger beneath the playing disk for removal. 100

5. A table for talking machines provided with an aperture therethrough; a filler bar for said aperture adapted to normally close said aperture and adapted to be pressed downwardly to permit removal of the play- 105 ing disk.

In witness that I claim the foregoing I have hereunto set my hand this 11th day of April, 1918.

GEORGE R. CUDLISS.
